UNITED STATES PATENT OFFICE.

PETER COOPER HEWITT, OF NEW YORK, N. Y., ASSIGNOR, BY MESNE ASSIGNMENTS, TO COOPER HEWITT ELECTRIC COMPANY, A CORPORATION OF NEW YORK.

METHOD OF REPRODUCING ELECTRICAL VARIATIONS.

SPECIFICATION forming part of Letters Patent No. 749,792, dated January 19, 1904.

Application filed May 16, 1902. Serial No. 107,602. (No model.)

To all whom it may concern:

Be it known that I, PETER COOPER HEWITT, a citizen of the United States, and a resident of New York, in the county of New York and State of New York, have invented certain new and useful Improvements in Methods of Reproducing Electrical Variations, of which the following is a specification.

In certain Letters Patent of the United States—for instance, those issued to me on the 17th day of September, 1901—I have shown and described gas or vapor electric lamps in which the resistance of the lamp can be kept practically constant by a suitable construction of the lamps. I have found that the resistance of these lamps is subject to control by other means than those set forth in the patents referred to and that the lamps may be used as a very sensitive means for varying the resistance of an electric circuit. For example, the resistance of these lamps is readily affected by a magnetic field in proximity to it, and the variations in the field may be made to reproduce themselves as a varying electrical resistance in the lamp. The same effect is produced by a magnet or solenoid upon an apparatus of this general character whether the apparatus is designed to operate as a lamp or light-giving medium or is especially designed as a means of varying the current in a circuit. In other words, in applying the described apparatus to the purposes of this invention I may so construct it as to make it capable of giving light, or I may prefer to inclose an appropriate gas or vapor in a container so proportioned as to accomplish the special results aimed at by this invention irrespective of whether the apparatus is then designed to produce light or not. In order to produce the desired variations of resistance in the gas or vapor apparatus, I generally locate the magnet or solenoid at the side of the apparatus, where it will distort the current passing between the positive and the negative electrodes, it being found that the active current in an apparatus of this sort tends to be deflected by a magnetic field. The stronger the magnet the higher the electrical resistance of the apparatus.

The present invention relates to means for applying this characteristic of my lamp or vapor apparatus to the purpose of reproducing the variations of current in an electric circuit whether a wholly independent circuit or a branch of a divided circuit. Such applications of the apparatus are useful for a variety of purposes, the action being a conversion of varying magnetic intensities, due to varying current affecting a magnetic field into variations of electrical resistance which may be made to affect a circuit in which my vapor apparatus is included.

In the accompanying drawings, Figure 1 is a diagram illustrating an organization of circuits for carrying out my invention, and Figs. 2 and 3 illustrate modifications.

Referring to Fig. 1, 1 represents a source of electric currents of any desired character connected in the circuit 3, which is provided with any suitable means 4 for varying the magnetic effects in a magnet 5. The magnet 5 is so placed with reference to a chamber 6, containing a conducting gas or vapor, which in turn is connected in a circuit 7, provided with any suitable source 8 of electric currents. The variations in the flow of current through the circuit 7 may be caused to act upon a receiving device 9 of any desired character. The means for varying the magnetic effects in the magnet 5 may, for example, be a telephone-transmitter, and the receiving device 9 may be a telephone-receiver. The gas or vapor within the tube or container is of any appropriate character, as more fully set forth in my patents hereinbefore referred to, and the negative electrode 10 may be of mercury or of any other suitable means for receiving the current from the gas or vapor and likewise the positive electrode 11, although for convenience I have in the drawings indicated it as being of a solid material held within the chamber 6. The location of the magnet 5 and its particular relation to the chamber 6 may be variously modified. In Fig. 1 I have represented the magnet with its core in a plane parallel with the chamber 6. In Fig. 2 it is illustrated as having one pole directed in a plane perpen-

dicular to the chamber 6, and in Fig. 3 I have shown the core as being prolonged, so as to partially or wholly embrace the chamber, thereby tending to direct the lines of force 5 transversely through the gas or vapor; but the constructions and positions of the magnet may be variously modified, the object being to cause the lines of force to pass into the vapor-path.

- 10. It is possible by means of my invention to produce in the secondary or receiving circuit electrical variations of greater magnitude than the original electrical variations of the primary or transmitting circuit. This is due to 15 the fact that a given magnetic variation may cause a wider fluctuation of effective resistance in the gas or vapor than the fluctuations of electrical energy producing the variation of the magnetic field of force. Accordingly by employing one of my lamps or vapor apparatuses as described I may magnify the vibrations of the circuit not by inductive effects but by varying the ohmic resistance of the circuit in 20 which the apparatus is included.
- 25. I have mentioned a telephone-circuit merely for purposes of illustration. The amplifications due to changes in resistance of my apparatus may be applied to other circuits as well, including circuits carrying currents of 30 large quantity. It will further be understood that the application of my invention is not limited to cases where it is desired to amplify the primary variations, but is useful also where it is merely desired to reproduce them 35 in the same or even less magnitude.
- 40. Means for starting the flow of current through the apparatus are set forth in the patents hereinbefore referred to.

I claim as my invention—

- 40. 1. The method of reproducing current variations in an electrical circuit, which consists

in transforming these variations into a varying field of force, causing the said field of force to act magnetically upon an inclosed gas or vapor so as to produce variations of electrical resistance in another circuit. 45

2. The method of producing in a circuit containing an inclosed conducting gas or vapor, variations of electrical resistance corresponding to variations of current in another 50 circuit, which consists in causing the variations of current in the second-named circuit to act magnetically upon the said gas or vapor and thereby vary the electrical resistance thereof and of the circuit. 55

3. The method of reproducing in a translating device included in a circuit containing an inclosed gas or vapor path, effects corresponding to electrical variations in another 60 circuit, which consists in converting said electrical variations into magnetic variations, and causing such magnetic variations to act upon an inclosed gas or vapor path, thereby producing variations in the current-flow of the first-named circuit. 65

4. The method of reproducing in a translating device included in a circuit containing an inclosed gas or vapor, effects corresponding to variations of electrical resistance in another circuit, which consists in causing in the 70 last-named circuit variations of current adapted to affect the translating device, converting these variations of current into magnetic variations, and causing such magnetic variations to act upon the inclosed gas or vapor. 75

Signed at New York, in the county of New York and State of New York, this 9th day of May, A. D. 1902.

PETER COOPER HEWITT.
